UNITED STATES PATENT OFFICE.

WILLIAM H. FRANCIS, OF CHERRYVALE, AND CHARLES FRANCIS, OF INDEPENDENCE,
KANSAS.

BRICK-HANDLING MACHINE.

No. 890,586.

Specification of Letters Patent.

Patented June 9, 1908.

Application filed December 12, 1907. Serial No. 406,236.

To all whom it may concern:

Be it known that we, WILLIAM H. FRANCIS and CHARLES FRANCIS, citizens of the United States, and residents of Cherryvale, in the county of Montgomery and State of Kansas, and Independence, in the county of Montgomery and State of Kansas, respectively, have invented an Improvement in Brick-Handling Machines, of which the following is a specification.

In the patent granted William H. Francis, July 9, 1907, No. 859,445, there is shown and described a machine for handling bricks in bulk, whereby a pile of bricks, stacked up in accordance with a pre-arranged order, may be picked up in bulk and transported to another point without breaking bulk. This machine requires the bricks to be stacked up with uniform spaces between the bricks of the basic layer so as to permit lifting arms to enter these spaces to carry the superposed load, while the basic layer was also picked up and carried along with the superposed load by the lateral pinching action of clamp plates below the lifting arms. When such load of bricks are set down again, the basic layer of bricks rests upon the floor to support the superposed bricks without imprisoning the lifted arms against the floor, so that the lifting arms could be easily withdrawn in horizontal direction without being held by the pinching weight of the load.

The present invention comprises novel means for doing this same work, and it consists in the improved construction and arrangement of the parts which we will now proceed to describe with reference to the drawing, in which

Figure 1 represents a perspective view of the rear of the machine. Fig. 2 is a perspective view taken from the front and showing the stack of bricks as picked up and suspended on the machine for transportation by a suitable crane or other lifting device. Fig. 3 is a rear elevation of the machine on a larger scale. Fig. 4 is a partial side view of the same partly broken away. Figs. 5 and 5^a are horizontal sections through one of the clamp plates taken on line 5—5 of Fig. 4, showing the closed and open positions respectively, and Figs. 6 and 6^a are enlarged vertical sections through a clamp plate on line 6—6 of Fig. 4, Fig. 6 showing the clamp plates closed, and Fig. 6^a showing them open or expanded for

clamping the bricks when inserted into the spaces between the bricks of the basic layer.

Referring to Fig. 2 which shows a stack of bricks held in suspension upon our machine, it will be perceived that the bricks of the basic layer are spaced apart a uniform distance of about one inch. Into these spaces are projected lifting arms which consist of vertical plates attached at one edge rigidly to an upright and braced frame, and free at the other edge. This upright frame seen in Fig. 1, is of a generally triangular shape, and consists—see Fig. 3—of the two inclined bars A, A, a central vertical bar A², vertical straps A', A', a transverse and horizontal bar A³, two triangular frames A⁴, A⁴, and a base bar A⁵. All of these parts are rigidly bolted together to form a unitary frame structure, and it has attached to its side bars A, A, upwardly extending wings or loops O, O. To the apex of this triangular frame there is pivoted upon the stout bolt a, a short lever section B, which on its long end is provided with an eye C to receive the lifting hook from a traveling crane. The short lever B has a limited movement on its fulcrum a, which is determined by a loop shaped link D connected at one end to the frame A, and at the other end embracing a bolt b. When the lifting strain is applied to the eye C, the lever B tilts upon its fulcrum a until the bolt b reaches the upper end of the link D. At this time the lever B and the main frame A become rigidly suspended. The initial upward movement of the lever B is made to perform certain work at the lower end of the frame for clamping the bricks as hereafter described, and for this purpose the short end of lever B is connected to two thrust bars E, E. These thrust bars E are pivoted at their lower ends to the inner arms of two elbow levers F, F. These levers are fulcrumed upon a bolt r, between the cross bar A³ and the vertical straps A'. The lower members of the elbow levers F are provided with suitable hooks which are connected to the opposite ends of a spiral tension spring G. At a point between the fulcrum r of each lever F and its lower end, there is pivotally connected a lift rod H. This lift rod passes through a horizontal lift bar I, and applies its lifting strain to a series of coil springs d. These coil springs d surround vertical stems c, and bear at their upper ends against screw nuts c', so that when the lifting strain of the

bar I is applied through the springs d, this lifting strain will be applied elastically to each one of the vertical stems c. The stems c at their lower ends are respectively pivoted 5 to corresponding disk shaped hubs K—see Fig. 4—which turn freely on a horizontal shaft J fixedly held in offsetting brackets R, rigidly attached to the base frame A⁵.

The base frame A⁵ is rigidly bolted to a 10 series of parallel laterally projecting lifting arms M, each one of which is of rectangular shape as seen in Fig. 4, and is provided on its opposite sides with two elastic plates m, m secured at their upper edges to the lifting 15 arm M, and at their lower edges free to be sprung apart and away from each other. At a point near the bottom of these spring plates m, m said plates are provided with inward 20 projections m', m³, m³, of a wedge shape as seen in Figs. 5 and 5^a. There are two of these projections m³, m³ on one side alternating with the one m' on the other side, m' passing between m³, m³ when closed as in Fig. 6, so as to give a greater expansion. 25 Pivoted to each one of the disk shaped hubs K there is a wedge shaped thrust bar L, which enters an opening in the end of the rectangular lift arms M, and penetrates between the spring plates m, m to a point of engagement 30 with the inward projections m', m³. When this thrust bar L is projected inwardly between such spring plates, its wedge shaped end passing between the projections m', m³, thrusts them apart as shown in Figs. 5^a and 35 6^a, and consequently increases the lateral dimensions of said spring plates, which causes them to form clamp plates which expanding against the sides of the bricks of the basic layer—seen in Fig. 2—causes the bricks 40 of this layer to be pinched with a lateral frictional engagement. The rigid arms M rest in contact with the bricks above the basic layer, and, when lifted, lift the superposed weight 45 of the bricks above, while expanding action of the clamp plates between the bricks of the basic layer pinches and holds the bricks of said basic layer with sufficient tightness as to maintain the unity of this basic layer along with the superposed bricks, permitting 50 them all to be transported in bulk intact.

When the machine is to be applied to a stack of bricks whose basic layer is spaced apart as before described, it is held in suspension by the crane, and is bodily thrust laterally against the stack of bricks in such position as to cause its several lifting arms to enter the spaces between the bricks of the basic layer, and for such manipulation a long loop-shaped handle P is attached to the base 55 frame A⁵.

To cause a more certain adhesion between the clamp plates and the bricks of the basic layer, the lower portions of the spring plates m, m are provided with small projections m², 60 which embed themselves slightly into the

bricks without producing any damaging effect thereon.

From the foregoing description, it will be seen that the principal portion of the lifting strain for carrying the load is sustained by 70 the rigid arms M, and that the initial lifting movement expands and sets the clamp plates to pinching engagement with the bricks. This initial lifting movement, transmitted through the lever B, puts a downward thrust 75 on the two thrust bars E, E—see Fig. 3. These throw the inner ends of the elbow levers F down, spreading the spring G under tension, and pulling upwardly the lift rods H, H, and the horizontal lift bar I. This 80 lift bar I applies its lifting strain through the coil springs d in an elastic manner to the stems c, and these in turn rotate partially the disk hubs K and project the spreading bar L between the two members of the clamp 85 plate. The coil springs d in this connection exercise an important function in that they give elastically an individual expansive action to each clamp plate, so as to cause any one clamp plate to expand to the full size of 90 its space existing between the bricks of the basic layer, independently of the other spreading device, and thus compensates for variations in the width of the spaces between the bricks of the basic layer. This insures 95 that all the bricks of the basic layer will be pinched and held whether of uniform spacing or not.

We claim—

1. A machine for handling bricks, comprising a vertically disposed frame, laterally extended arms carried by the lower end of said frame, expandable clamp plates arranged beneath each laterally extended arm, means for expanding said clamp plates, and means 100 for operating the same by the initial movement of the lifting strain.

2. A machine for handling bricks, comprising a vertically disposed frame, laterally extended arms carried by the lower end of 110 said frame, expandable clamp plates arranged beneath each laterally extended arm, means for expanding said clamp plates, means for operating the same by the initial movement of the lifting strain, and an individual lifting 115 spring interposed in the train of the expanding devices for each clamp plate.

3. A machine for handling bricks, comprising a vertically disposed frame, laterally extended arms carried by the lower end of 120 said frame, expandable clamp plates arranged beneath each laterally extended arm, means for expanding said clamp plates, means for operating the same by the initial movement of the lifting strain, an individual lifting 125 spring interposed in the train of the expanding devices for each clamp plate, and a horizontal lift bar connected to and applying the lift strain simultaneously to all of said lifting 130 springs.

4. A machine for handling bricks, comprising a vertical frame of triangular shape having its apex at the upper end, and laterally projecting lifting arms and clamping plates at the lower ends, and offsetting and steadyng wings arranged at the upper end of the triangular frame.

5. A machine for handling bricks, comprising a vertical frame, with laterally projecting lifting arms, clamping plates at their lower ends, said plates being made of two expansible members, a wedge shaped thrust bar arranged to be projected between said expanding members, a horizontal shaft having loose hubs with crank pins connected to said thrust bars, and lifting devices arranged to rotate said loose hubs.

6. A machine for handling bricks, comprising a vertical frame, with laterally projecting lifting arms, clamping plates at their lower ends, said plates being made of two expansible members, a wedge-shaped thrust bar arranged to be projected between said expanding members, a horizontal shaft having loose hubs with crank pins connected to said thrust bars, and lifting devices arranged to rotate said loose hubs, said lifting devices consisting of stems attached to the loose hubs, each having a nut at its upper end, and a spiral spring wound around the stem below the nut, a horizontal lift bar bearing upwardly against all of said springs, lift rods connected to said lift bars, spring actuated levers connected to the lift rods, and thrust bars for the levers arranged to be projected downwardly by the lifting strain.

7. In a machine for handling bricks, the combination with the upright frame, of rigid laterally projecting lift arms having on their opposite sides spring plates free at their lower edges and provided with inward projections, and a wedge shaped thrust bar arranged to be projected between the spring plates to expand the same.

45 8. In a machine for handling bricks, the combination with the upright frame, of rigid laterally projecting lift arms having on

their opposite sides spring plates free at their lower edges and provided with inward projections, and a wedge shaped thrust bar arranged to be projected between the spring plates to expand the same, said spring plates being formed along their lower edges with external projections adapted to clutch the bricks.

9. In a machine for handling bricks, an upright triangular frame comprising two equally inclined side bars, a base bar attached to the lower ends of the same, triangular brace frames arranged at the lower ends of the inclined side bars between the same and the base bar, a horizontal transverse bar arranged above the base bar, levers pivoted thereto, means for producing a thrust upon said levers, lifting rods attached to the levers, a horizontal lift bar attached to the lift rods, a series of horizontally projecting lifting arms for the base bar, expansible clamp plates arranged below the same, and means for individually expanding the same by the upward movement of the lift rod.

10. A machine for handling bricks, comprising an upright frame having at its lower end rigid laterally projecting lifting arms, and clamp plates arranged beneath the same, and in the same plane therewith, a lifting device for the frame, and means for utilizing the initial movement of the lifting device for the expansion of the clamp plates.

11. In a machine for handling bricks, the combination with the carrying frame, of a lever pivotally mounted to the upper end of the same, and having on one side of its fulcrum a lifting eye and a stop link for determining the amount of deflection of said lever, and a thrust mechanism connected to the other side of its fulcrum, and brick clamping plates arranged to be set into clamping action by said thrust mechanism.
